UNITED STATES PATENT OFFICE

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,108,110.

Specification of Letters Patent. Patented Aug. 18, 1914.

Application filed September 23, 1913. Serial No. 791,293.

To all whom it may concern:

Be it known that I, WALTER S. ADAMS, a citizen of the United States, and a resident of Philadelphia, county of Philadelphia, and State of Pennsylvania, and whose post-office address is care of The J. G. Brill Co., Sixty-second street and Woodland avenue, in said city, have invented certain new and useful Improvements in Car-Trucks, of which the following is a specification.

My invention relates to improvements in swing bolster car trucks, and particularly to that class wherein semi-elliptical or leaf springs or other equivalent form of bolster supports are carried from the side frames of the truck by swinging links or hangers.

My present invention consists in certain details of construction and combination of parts hereinafter described, and finally pointed out in the claims.

In the drawing, forming part of this specification, Figure 1 is a side elevation showing a portion of the side frame of a car truck and the improved bolster connection supported therefrom; Fig. 2 is a side elevation and a section of a portion of the side bar, the section being taken on the line 2-2 of Fig. 1, looking in the direction of the arrows; and Fig. 3 is a sectional elevation on the line 3-3 of Fig. 1, looking in the direction of the arrows.

Similar reference characters designate like parts throughout the several views.

For the purpose of describing my invention, I have not deemed it necessary to illustrate an entire truck construction, as those skilled in the art are familiar therewith. However, for the purpose of further illustration, reference is made to the truck shown in the patent dated October 14, 1913, No. 1,076,009.

In the drawing, 1 is an intermediate portion of the side frame or upper chord of the car truck frame. This is usually provided with pedestals of conventional or desired construction.

It will be understood that all of the parts hereinafter described, except the bolster, are duplicated at each side of the truck, the pedestals engaging axle boxes which hold axles and wheels in the usual manner. The side frame or upper chord is connected transversely of the usual transoms 2 shown in dotted lines in Fig. 1.

At 3 are hangers comprising the splayed side bars 4, 5, parallel bars 6, 7, bent ends 8, 9 and curved cross piece 10, which hangers embrace the side bars and rest at their upper ends 10 on bearings 11 the lower ends carrying blocks 12 forming spring-seats. A form of hanger of the class described is shown in my said application.

At 13 is the leaf spring, which, in the present case, is flat, although it may be arched upwardly. As above stated, it will be understood that there are two of such springs, one on each side of the truck, and disposed longitudinally below the plane of the side bars.

At 14 is the bolster, shown in the present case as a casting having an enlarged intermediate section 15 adapted to pass between the transoms and outer ends or extensions 16 passing underneath and clearing the side bars of the truck frame.

The leaf springs are provided with the usual strap or band 17 at their center, and upon this band is seated the bolster ends 16, recesses being provided for this purpose.

At 18 is a recessed plate receiving the band 17, and bolts 19 secure the bolster, plate and spring together, thereby tying the springs 13 and hangers 3 together.

At 20 are spring-caps provided with flanges 21 engaging the faces of the side bars 6, 7 of the hangers 3 and lips 22 which engage the sides of said side bars, and which form, with the web 23 of the cap a spring-seat for the ends 24 of the leaf spring 13, which bear on the caps 20. The caps 20 rest on spiral springs 24 each seated in the seats 12. The spiral springs are thus held entirely within the strap hangers 3, the leaf springs supported directly thereon, and relative movement of the springs guided and restrained by the side bars of the hangers, whereby an articulated type of hanger may be dispensed with.

Within the scope of the appended claims, my invention may be variously embodied without departing from its spirit.

Having described my invention, I claim:

1. In a car truck, the combination with the side bars, the hangers movably supported on the side bars and comprising paired bars, a spring seat on the bottom of each of said bars, a spring seated on said spring seat, a spring cap on said spring and guided by said

bars, longitudinally disposed leaf springs supported on said spring caps, and a cross bolster supported on said leaf springs.

2. The combination with a car truck, of 5 the hangers comprising paired bars movably supported from the side bars of said truck, spring seats at the bottom of said hangers, upwardly extending spiral springs on said seats between the said bars, spring caps on 10 said spiral springs guided by said arms, longitudinally disposed springs extending between said bars and resting on said spring caps, and a cross bolster connecting the leaf springs.
- 15 3. In a car truck, the combination with the truck side bars of the hangers comprising paired bars, the upper portions of which are

splayed outwardly, the lower portions of which are parallel, spring seats at the bottom of said hangers, springs on said spring 20 seats, spring caps on said springs guided by said parallel bars, longitudinally disposed leaf springs extending into the hangers and having their ends resting upon said spring caps, and a cross bolster secured to said leaf 25 springs.

Signed at the city and county of Philadelphia, State of Pennsylvania, this 15th day of August, 1913.

WALTER S. ADAMS.
